UNITED STATES PATENT OFFICE.

JOHN C. BLACK, OF DESTREHAN, LOUISIANA.

PROCESS AND APPARATUS FOR TREATING HYDROCARBONS TO PRODUCE THOSE OF LOWER BOILING POINTS.

Application filed August 15, 1921. Serial No. 492,377.

To all whom it may concern:

Be it known that I, JOHN C. BLACK, a citizen of the United States, residing at Destrehan, in the parish of St. Charles and State of Louisiana, have invented a certain new and useful Process and Apparatus for Treating Hydrocarbons to Produce Those of Lower Boiling Points, of which the following is a specification.

This invention relates to the dissociation or conversion of high boiling-point hydrocarbons derived from crude petroleum or its equivalent, into those of lower boiling-point, and to an apparatus especially useful in increasing the production of, so-termed, gasoline from relatively heavy hydrocarbons having high boiling points. It is known that by the apparatus and processes at present employed for producing gasoline without cracking, a comparatively small percentage, from a fraction of one per cent to thirty per cent or more gasoline, is obtained by ordinary distillation of the crude oil.

The apparatus and processes commonly in vogue for producing gasoline, other than that produced by ordinary distillation of the crude oil, rely fundamentally upon heating the hydrocarbons to certain temperatures under pressure to produce cracking, taking the vapors off at a high temperature under the pressure employed and condensing the same. As distinguishing fundamentally from such pressure-vapor processes, my present apparatus performs what, for brevity, may be termed a pressure-liquid process, since I do not vaporize the hydrocarbons to any material degree while at cracking temperature, but rather, maintain a pressure on the hydrocarbons above the vapor pressure thereof at the cracking temperature employed, then reduce the temperature of the whole body of hydrocarbons, while they are under the pressure employed, to such a point as may be desirable for subsequent treatment thereof. If the hydrocarbons, as treated, are reduced to normal temperature they will have the appearance of crude oil with many of its characteristics and they may be termed a "crude equivalent."

In this improved apparatus I not only maintain pressure on the hydrocarbons un-

der treatment to prevent any material vaporization thereof, but I preferably maintain them at cracking temperatures while in liquid form for a prolonged period of time and retard flow of the liquid hydrocarbons while at cracking temperature so that dissociation and polymerization will be as complete as possible before the hydrocarbons are cooled or subjected to the subsequent treatment required to separate the low boiling from the high boiling hydrocarbons. I maintain pressure on the hydrocarbons under treatment until they are cooled if the immediate object is to crack and store the product for subsequent treatment as hereinafter described. If, however, it is desired to crack and then immediately distill, pressure is maintained on the hydrocarbons under treatment during the cracking, dissociation and polymerization of the hydrocarbons, after which distillation of the hot hydrocarbons at atmospheric or higher pressure will be effected in any suitable distilling and fractionating apparatus, two examples of which will be described hereinafter.

To maintain the liquid hydrocarbons at cracking temperatures for the prolonged period of time and at the same time to cause the deposition of carbon produced by the cracking operation, I preferably reduce the speed of flow of the liquid hydrocarbons while they are at the cracking temperatures and, in this particular instance, I accomplish this by discharging the heated hydrocarbons from the cracking or heating coil into a "digester," as I term it. This digester is a combined cracking chamber and carbon catcher of larger cross sectional area than that of the cracking coil tubes.

In the operation of my apparatus, I may treat for the production of gasoline the intermediate "cuts," resulting from first subjecting crude petroleum or a crude equivalent to any of the heretofore known distillation processes. By such first distillation process there may result, for example, gasoline amounting in volume to from 15 to 20 per cent more or less; asphalt, coke and the like, 20 per cent; and intermediates, 65 per cent, more or less. The percentages given are only approximate and may vary considerably with petroleum from different lo-

calities. These intermediates, when treated in my apparatus, are changed into a "crude equivalent" which is then fractionated at once in the apparatus to separate the fractions or "cuts" desired, or allowed to stand in storage for a time and then fractionated. It is understood that the fractionating may be performed in any suitable apparatus other than disclosed in the drawings. An advantage that arises in not fractionating immediately is that the yield of lighter hydrocarbons is thereby increased.

The accompanying drawings illustrate an apparatus embodying the invention:

Figure 1 is a more or less diagrammatic elevation, partly in section, of the apparatus; and

Figure 2 is a sectional elevation on line indicated by x^2-x^a , Figure 1.

The apparatus illustrated in the drawings is constructed as follows: In a furnace A there is provided a suitable lower combustion chamber 1 having at one end thereof a burner 2 and having at its opposite end an opening 3 through which the products of combustion can pass into a coil-heating chamber 4. In the coil-heating chamber 4 is a cracking coil 5 which is heated by the products of combustion that pass through the chamber 4. The coil-heating chamber 4 is provided at the end opposite that having the opening 3 with an opening 6 through which the products of combustion escape into an upper combustion chamber 7 provided at one end with a burner 8. Thus the chamber 7 is not only heated by the products of combustion from the burner 2 but may be heated additionally by fire from the burner 8.

From the combustion chamber 7 the products of combustion flow through an opening 9 into an intermediate coil-heating chamber 10 having a pre-heating coil 11. The products of combustion flow from the chamber 10 through an opening 12 into an upper coil-heating chamber 13 in which is positioned a heating coil 14. From the chamber 13 the products of combustion discharge through a flue 15. The fuel furnished to the burners 2, 8 may be gas or oil and the burners are capable of raising the various chambers to the temperatures required for performing the process in the apparatus.

The coils 5, 11 comprise a number of straight tubes 16 which pass through perforations 17 in the front and rear walls of the chambers 4, 10. The coils 5, 11 further comprise headers 18 connecting the ends of adjacent tubes to one another. The headers 18 are provided with removable plugs 19. Thus it is clear that the coils 5, 11 may be readily cleaned when such cleaning becomes necessary or desirable. The outlet end of the coil 5 is provided with a pyrometer 20

so that the temperature of said coil and its contents may be noted from time to time during the operation of the apparatus. The outlet end of the coil 5 is connected by a tube 21 to a "digester" or combined cracking chamber and carbon catcher 22, preferably of larger cross sectional area than the cracking tubes 16. The digester 22 may be formed of a piece of relatively large tubing and removable heads 23 are fitted to the opposite ends of the tubing to form tight closures therefor. The heads 23 are detachably held in place by yokes 24 and screws 25. Connected with the digester 22 is a blow off line 94 which is provided with a valve 95 and which may be connected to a receiver, not shown.

The digester 22 is connected by a tube 26 to a heat interchanger 27, said tube 26 being connected with the inner tube 28 of the interchanger. The outer tube 29 of the interchanger is connected by tubing 30 to one end of the coil 14 and the opposite end of said coil is connected by tubing 31 to one end of the coil 11. The outlet end of the coil 11 is connected by tubing 33 to the opposite end of the coil 5 from that provided with the pyrometer. The outer member 29 of the heat interchanger is connected by tubing 34 with a pump 35 which receives liquid hydrocarbons through a supply pipe 36 connecting with a tank 37. The tubing 34 is provided with a pressure gage 38. A by-pass 96 connects the tubing 30 to the tubing 34 and is provided with a valve 97 so that the heat interchanger may be cut in and out at will.

The inner tube 28 of the heat interchanger is connected by tubing 39 to one or more fractionating stills 40 of any desired construction. When more than one still is employed, the stills are connected to one another by cross-overs 41 for continuous operation provided with pressure regulator and discharge valves 98. If so desired, each still may be operated independently of the other, each receiving its supply of oil from 39 through the valve 43, the cross-overs 41 being blanked off. The stills are each provided with a pressure gage 99. The tubing 39 is provided with a valve 42, and between said valve 42 and the valve 43 with a pressure regulator and discharge valve 44, said pressure regulator serving to keep the requisite pressure on the liquid hydrocarbons in the cracking coil 5 and cracking chamber 22 and also in all other parts of the apparatus between the pressure regulator and the pump 35. The tubing 39 is also preferably provided with a carbon catcher 100 having a discharge pipe 101 controlled by a valve 102.

Each still 40 is connected by tubing 45 to a condenser 46 and each tubing 45 is provided with a pressure regulating discharge valve 103. Each condenser is connected by 5 a tube 47 to a gas trap 48; each gas trap 48 is connected by tubing 49 to a gas absorber 50 and the gas absorbers are provided with gas vent pipes 51 to carry the gas to any desired place. Each gas trap 48 is 10 connected by a tube 52 to a sampling box 53 and each sampling box is connected by tubing 54 to a storage tank 55. One or more of the storage tanks 55, in this instance, two of them, are connected by tubing 56 15 to the tubing 36. The tubing 56 is provided with valves 58 and the tubing 36 is provided with a valve 59.

The tubing 39 is connected by tubing 60 with a cooler 61 which in turn is connected 20 by tubing 62 to a gas trap 63. The tubing 62 is provided with a pressure regulator 64 and a pressure gage 65 between the pressure regulating valve and the cooler. Also the tubing 62 is preferably provided between the 25 valve 64 and gage 65 with a carbon catcher 104 having a discharge pipe 105 controlled by the valve 106. The gas trap 63 is connected by tubing 66 to a gas absorber 67 and the gas absorber is provided with a gas 30 vent tube 68. The gas trap 63 is connected by tubing 70 to a storage tank 71. The tubing 60 is provided with a valve 72 and the tubing 39 is provided with a pressure gage 73. To the tubing 70 is connected a tubing 35 35 74 having a valve 75, and the tubing 74 connects with the tank 37. The tubing 70 is provided between the tubing 74 and the tank 71 with a valve 76. The tubing 34 is provided with a valve 107 between the by- 40 pass 96 and heat exchanger 27.

The process described and claimed in my co-pending application filed December 12, 1919, Serial No. 344,406, is performed in the above described apparatus as follows: The 45 tank 37 will be supplied with the hydrocarbons to be treated. Crude petroleum or a crude equivalent may be employed, but I preferably use the intermediate fractions resulting from treating crude petroleum or a 50 crude equivalent, by prior known processes. Among such intermediate fractions, for example, are those which are not capable of being further cracked by the relatively low-pressure processes to produce the much desired low boiling-point hydrocarbons. The 55 valves 59, 72, 75 and 107 are opened and valves 42, 58, 76 and 97 are closed and the pump 35 is operated to force liquid hydrocarbons from the tank 37 through the system 60 and to produce a pressure of several hundred pounds in that portion of the system between the pressure regulator 64 and the pump, thus insuring that said portion is entirely filled with the liquid hydrocarbons which are to be treated. Air may be ex-

cluded from this portion of the system through the tank 37. The fires are then started at the burners 2, 8 so as to heat the coils 5, 11, 14 to the required temperatures.

The pump is continued in operation and the hydrocarbons circulate continuously while they are being heated to the required temperature. Until cracking has taken place to a satisfactory degree the oil is bypassed through valve 75 and tubing 74 to tank 37 to be re-run through the cracking tubes and digester. The pyrometers 20, 32 will be consulted to determine the temperature of the hydrocarbons in the coils 5, 11. 70 75 80 The temperature of the coil 11 will be preferably maintained just under that required for cracking of the hydrocarbons, though if the temperature should rise higher and an incipient cracking of the oil take place the tubes may be readily cleaned of carbon deposits when they become choked. The coil 5 is heated to a predetermined cracking temperature.

The degree of pressure employed is pre-determined for the particular hydrocarbons being treated. The temperature required for the particular hydrocarbon being treated may be determined by the increase of gravity of a sample, supplemented usually by a 95 distillation test to determine the yield of hydrocarbons boiling between certain specific temperature limits.

Assuming that one or more of the stills 40 is to be utilized, that the predetermined cracking temperature has been reached, and that the regulator 44 has been set for the predetermined operating pressure, the valves 42, 43, 77 will be opened and the valves 58, 72 will be closed, thus causing the hydrocarbons to flow into the still or stills when the desired degree of cracking is reached. The pump 35 is continued in operation so as to maintain the desired pressure rearwardly of the pressure regulator 44 and so 100 as to cause the hydrocarbons to flow under such pressure through the various coils and through the cracking chamber 22. The pressure prevents any material vaporization in the cracking coil 5 and digester 22, 110 though it may be possible that some of the lightest of the hydrocarbons may vaporize under some of the pressures which I may desire to use in the apparatus. Before the liquid hydrocarbons discharge from the 115 cracking coil 5 they reach the cracking temperature and the time of subjecting the liquid hydrocarbons to the cracking temperature is prolonged by reason of the liquid hydrocarbons discharging from the coil 5 through the tubing 21 into the digester 22. In the digester 22 the rate of flow of the liquid hydrocarbons decreases because of the 120 relatively large cross sectional area of the digester. The digester 22 is suitably insu- 125 130

lated against loss of heat and thus the liquid hydrocarbons are maintained at cracking temperature during their flow through the digester.

5 Not only does the digester 22 prolong the cracking operation so as to insure that the cracking of the liquid hydrocarbons at the given temperature is complete or substantially complete; but deposition of carbon 10 occurs in the digester to a much larger extent than in the coil 5, for the reason that the flow of liquid hydrocarbons is slower in the cracking chamber than in the coil 5, thus permitting the free carbon produced in 15 the cracking operation to become attached to the relatively large wall area of the digester.

From the digester 22 the cracked hydrocarbons, still in the liquid state at comparatively high temperature, flow through 20 the heat interchanger 27 where they are cooled to a greater or less degree, depending upon the area of the radiating surface of the heat interchanger. Thus a predetermined amount of heat is absorbed in the interchanger by the cooler hydrocarbons being fed into the system by the pump 35, and the heat interchanger serves to initially heat 25 the hydrocarbons being treated. Further heating of the hydrocarbons is effected, between the heat interchanger and the coil 11, in the coil 14, around which flow the hot waste gases passing from the chamber 10 through the chamber 13 to the flue 15.

30 The cooling capacity of the interchanger 35 may be such as to cause those hydrocarbons which are liquids at ordinary temperatures and pressures to remain liquid when the artificial pressure is entirely removed.

40 That is to say, if it is not desired to immediately fractionate the cracked hydrocarbons, they may be discharged into the tank 71 by opening the valves 72, 76 and closing the valve 42; that, if the cooling capacity 45 of the interchanger 27 be sufficient, the lighter as well as the heavier hydrocarbons in the crude equivalent will discharge as liquids without running them through supplemental cooling means; and that, if the 50 cooling capacity of the interchanger is not sufficient to prevent vaporization of the cracked hydrocarbons upon release of the pressure through the valve 64, then the cooler 61 will be operated to complete this cooling 55 operation. I have discovered that, by allowing the crude equivalent to stand for a more or less extended period of time to permit of further polymerization in the tank 71 before fractionating upon subsequently fractionating 60 the crude equivalent it yields a greater percentage of the more stable lighter hydrocarbons desired, hence the advantage of immediately cooling the cracked hydrocarbons to a temperature sufficiently low to prevent 65 vaporization of all of them and produce the

mixture which is termed a "crude equivalent." When, however, the valve 42 is open and valves 72, 76 closed the hydrocarbons are treated at once in the still and hence it will not be necessary or desirable to cool them to 70 ordinary temperatures, and consequently less fuel will be required in the stills 40 to effect distillation. If it be not desired to effect cooling of the cracked hydrocarbons by operation of the heat interchanger 27 the 75 incoming hydrocarbons may be by-passed by closing the valve 107 and opening the valve 97.

The liquid hydrocarbons, after parting with at least some of their heat in the interchanger, 27, will discharge into the first still 40 and the first cut or lightest vapors will be carried over into the associated condenser 46. If continuous distillation is employed the unvaporized heavier hydrocarbons will flow from the first still into the second still through the cross-over 41 and another cut will be made and the second cut vapors will discharge into the associated condenser. Also from the second still the 80 yet heavier unvaporized hydrocarbons will discharge into the third still through the cross over 41 and the third cut vapors taken off from the third still will discharge into the associated condenser 46. Whatever gas remains after the vapors pass through the condensers will pass into the absorbers 50 and may be recovered in part in a manner well understood in the art to which this invention relates. To achieve the distilling just 85 described the stills will, of course, be progressively heated from left to right.

It will be understood that not only are the stills 40 progressively heated, but that, if desired, the pressure may be progressively 90 reduced or stepped down in the stills from left to right by proper adjustment of the valves 98, 103 and of the draw-off valve 109 on pipe 110 discharging from the last still 40, the stills thus constituting expansion or 95 vaporizing chambers. This enables me to vaporize the various light fractions while they are still under pressure, thereby preventing to a large extent the production of 100 olefines and unsaturated hydrocarbons. Of course, if desired, this fractionating by stepping down the pressure may be effected 105 without applying heat to the stills 40, for by properly adjusting the valves 98 and 103 only those hydrocarbons whose vapor tension or pressure is equal to or in excess of 110 that imposed by the valves 98 and 103 will vaporize and escape to the respective condensers. The residue that accumulates in the first and second expansion chambers 115 passes therefrom into the next succeeding chambers 40, respectively, under lower pressure so that the second and third cut hydrocarbons will vaporize and be condensed in the associated condensers. Any number of 120

125 65 vaporization of all of them and produce the

chambers may be utilized for vaporizing under reduced pressures each one giving a different fraction, depending upon the pressure and temperature of the hydrocarbons 5 entering the different vaporizing chambers.

The condensates pass from the condensers 46 through the tubing 54 into the storage tanks 55. In this instance, the lighter or lower boiling point hydrocarbons, which it 10 is the desire of the refiner to recover, are given off in the first still, the intermediate fractions are given off in the second and third stills and the carbonaceous matter or residue is deposited in the third still. It 15 may be assumed, for example, that the condensate from the first still is approximately 56° Baumé, that the condensate from the second still is approximately 35° Baumé and that the condensate from the third still is approximately 20° Baumé. These heavier 20 products or intermediate fractions produced in the second and third stills will be discharged from time to time from the storage tanks 55 containing them through the pipe 56 into the pipe 36 by opening the valves 58 and closing the valve 59, thus permitting the pump 35 to force the intermediate fractions again through the coils 5, 11, 14 and cracking chamber 22 to be re-cracked. The 25 intermediate fractions from the second and third stills 40, however, may be re-run independently through any suitable still for re-distillation so as to separate the lighter fractions from the heavier, and such lighter fractions may then be thrown in with the 30 distillates from the first still and the heavier fractions may be stored and then re-run through the apparatus.

If it be not desired to distill the liquid 40 cracked hydrocarbons at once, the valves 42, 75 will be closed and the valves 72, 76 opened, and the liquid cracked hydrocarbons will then flow from the tubing 39 through the tubing 60 into the cooler 61. 45 This cooler 61 may be dispensed with if the heat interchanger 27 is made of sufficiently great cooling capacity to absorb substantially all of the heat artificially applied to the hydrocarbons. The cooler liquid hydrocarbons pass from the cooler 61 through the tubing 62 and pressure regulating valve 64 into the separator 63 and the liquid hydrocarbons flow from said separator 50 through the tube 70 into the storage tank 71. The hydrocarbon in the storage tank 71 is termed a "crude equivalent" since it 55 resembles to a large degree crude petroleum. This crude equivalent at any desired time after its production will be fractionated to segregate the low boiling-point hydrocarbons desired from those of higher boiling-point.

Though the above described process performed in this apparatus differs considerably from the process of refining crude pe-

troleum oil patented to George L. Benton May 25, 1886, No. 341,564, and though said Benton process was conceived for the purpose of producing a different product, namely an illuminating oil, than the foregoing described apparatus produces, I employ the relatively high temperatures and pressures of the Benton process in the cracking operation; but, instead of spraying the hydrocarbons at cracking temperature 70 into a vaporizing chamber to produce the homogeneous illuminating oil of the Benton process, I effect a prolonged cranking operation under pressure, reduce the rate of flow of the liquid hydrocarbons while at 75 cracking temperatures, then reduce the temperature of the cracked liquid hydrocarbons to or below the vaporizing temperature of the low boiling-point hydrocarbons which it is desired to recover, and finally fractionate the hydrocarbons thus reduced in 80 temperature.

I have discovered that the yield of low boiling point hydrocarbons is very materially increased by prolongation of the heat 85 and pressure necessary for cracking, and I obtain this prolongation in the apparatus illustrated by use of the digester 22, which also, as had been noted above, reduces the rate of flow of the liquid stream. In this 90 manner I am enabled to produce a greater volume of low boiling point hydrocarbons from a given quantity of crude petroleum or a crude equivalent than is possible by prior known processes and in prior known 95 apparatus. For this reason the process is very useful and valuable since the production of low boiling point hydrocarbons such as gasoline by present known processes can scarcely keep pace with the increasing 100 demands therefor, mainly as fuel for internal combustion motors. Also by prior known low pressure processes there is produced an intermediate fraction which, by former known processes and apparatus, 105 could not be cracked, and which I am enabled by this process to crack to produce high grade gasoline. I prefer to treat any of the intermediate fractions in this apparatus, rather than crude oil, because the 110 prior distillation removes a large amount of carbonaceous material which thus cannot act to foul the apparatus.

The hydrocarbons of relatively high boiling point produced in the second and third 115 stills, in this instance, will be preferably re-run through the apparatus and cracked, and for this purpose, when quantities of the relatively high boiling point hydrocarbons have been produced by the still, the valve 59 120 will be closed and the valves 58 will be opened to permit the pump 35 to force such hydrocarbons through the system for cracking and redistillation. From this it is clear that in 125 this apparatus the process may be a continua-

ous one, not only in the sense that new supplies of oil are constantly being treated, but that a relatively large proportion of the product is re-run from time to time to eventually crack the relatively high boiling-point hydrocarbons circulating through the apparatus, thus enabling the production of possibly 50 per cent or more of low boiling-point hydrocarbons from the original stock treated.

The fractionating may be accomplished in any other suitable apparatus than described above, and, as an example of another fractionating apparatus which may form a part of the system, I may fractionate them by running them through fractional condensers, and for this purpose I have shown in the drawings a distillation vaporizing chamber 79 which is connected by tubing 80 to the tubing 39 between the pressure regulating valve 44 and a valve 77 on the tubing 39. The chamber 79 is connected by tubing 81 with the first of a series of fractional condensers 82, the coils of which discharge into gas or vapor traps 83. The gas traps are connected by tubes 84 with sampling boxes 85. The vapor trap 83 of the first condenser is connected with the coil of the second condenser, and the vapor trap of the second condenser is connected with the coil of the third condenser by tubing 86, respectively. Each of the sampling boxes 85 is connected by tubing 87 to a suitable receptacle or tank, the tubes 87 being provided with valves 88, respectively. For example, the discharge pipe 87 of the first condenser 82 may be considered as being connected with the first tank 55 beginning at the left in Figure 1 of the drawings, the tubing 87 of the second condenser as being connected with the second tank 55, and the tubing 87 of the third condenser as being connected with the tank 55 at the right side of Figure 1. These connections with the tanks 55 are not shown since it would tend to congest the drawing to show them, but it is understood such connections exist so that the heavier and lighter intermediate fractions from the first and second condensers 82 may be readily re-run through the apparatus for re-cracking in a manner hereinbefore described. The gas trap of the third condenser is connected by a tube 89 with a gas absorber 90 provided with a vent pipe 91. A pipe 92 having a valve 93 discharges from the chamber 79.

Preferably the tubes 81 and 86 are provided with pressure regulating and discharge valves 108 so that, by the proper adjustment thereof together with valves 88, 93 and valve 111 on tube 89, the pressure may be stepped down from the chamber 79 to the first condenser, from the first to the second and from the second to the third; thereby controlling not only the temperature of the

hydrocarbons in making the various cuts, but also predetermining the pressure at which the cut is made. Thus, instead of maintaining the cracked hydrocarbons at the cracking pressure while condensing, or reducing the pressure to atmospheric while condensing, or condensing all of the cuts at any pressure between that of cracking and atmospheric, all of which are made possible by proper adjustment of the valve 44, the condensing in the different condensers 82 may be effected at different pressures by proper adjustment of the valves 108, 88, 93 and 111.

In order to fractionally condense the cracked hydrocarbons, the valve 77 on the tubing 39 will be closed, as well as the valve 72, and the valve 78 will be opened, thus allowing the hot liquid hydrocarbons discharging through the pressure regulator 44 to vaporize in the chamber 79. The tarry products or other carbonaceous matter thrown down in the chamber 79 may be drawn off through the pipe 92. It is understood that the temperature of the hydrocarbons in tubing 39 and connecting tubing 80, will be sufficiently high under the pressure employed to cause the vaporization of the desired distillates, which in turn are fractionally condensed by proper regulation of the appropriate valves. The hot vapors pass from the chamber 79 into the first condenser 82 which will be made of such cooling capacity as to condense the heavier intermediate hydrocarbons that will then flow to the appropriate tank. The uncondensed vapors will pass from the first gas or vapor trap 83 through the tubing 86 into the second condenser which will be of such cooling capacity as to condense the lighter intermediate fractions. These lighter intermediate fractions will then discharge from the associated vapor trap 83 and pass to the appropriate tank and the uncondensed lighter vapors will pass over into the third condenser through the associated tubing 86. The third condenser will be of sufficient cooling capacity to cause condensation of the low boiling-point fractions which it is the desire of the refiner to produce and such fractions will discharge from the associated vapor trap 83 and pass to the appropriate tank. The gas may pass from the third gas trap through the tubing 89 into the gas absorber 90 where certain low boiling-point fractions may be recovered, in a manner well understood in the art to which this invention relates.

By appropriate adjustment of the pressure regulating valves 108, 88, 93 and 111 to step down the pressure, sudden release of pressure while the hydrocarbons are at high temperature is avoided and the different cuts may be made so as to prevent in great measure the production of olefines and unsaturated hy-

drocarbons which might result if the pressure were wholly or almost completely released while the oil is still at cracking temperature. Thus I am enabled to avoid low pressure cracking which tends to produce olefines and unsaturated hydrocarbons.

It is understood that re-distillation and re-running through the apparatus of the intermediate fractions thus resulting may be effected in the same manner as above described for the fractions produced by the stills 40. The same cuts or fractions may be produced in the series of condensers 82 as are produced by the stills 40. It is understood that the cooling capacity of the heat interchanger 27 or any other suitable cooling means may be such that the temperature of the liquid hydrocarbons will be reduced from that required for cracking to that which will produce in a single vaporizing and condensing operation the low boiling point fraction desired; or that after such cooling the temperature will be reduced only enough to produce by evaporation and fractional condensation one or more of the intermediates above referred to. The remaining uncondensed vapors will then be condensed as above described to produce the low boiling point fraction desired. Though the various fractions may be produced by the fractional condensing described above, there may be, in practice, advantages in fractionating the hydrocarbons by the fractional distillation operations previously described, by fractionating towers or other apparatus, but the ultimate result is in a measure the same whichever fractionating operation is employed.

The cracking operation is continued in the coil 5 and cracking chamber 22 until the increasing differential pressure between the gages 38, 73 or 38, 65, as the case may be, denotes such increased resistance to the flow of the oil as to indicate that said coil or the digester 22 is seriously fouled with carbon, rendering the apparatus inoperative; whereupon the fires are shut off and the fouled tubes 16 and digester 22 are cleaned, the cleaning operation being facilitated by removal of the plugs of the headers and the heads 23 of the digester, thus to allow each tube and the digester to be separately cleaned of the carbon deposited therein. Or, before differential pressure occurs, cleaning may be effected by blowing out with air or steam or both.

The higher the temperature and longer the time employed for cracking the hydrocarbons the larger will be the yield of low-boiling-point hydrocarbons and the greater will be the production of carbon, so that in a practical commercial plant it is necessary for the operator to choose such a temperature and pressure and duration of such temperature and pressure that as long a run as possible may be made, without the necessity of

cleaning out the carbon, consistent with a sufficient yield of gasoline to make the operation of the plant profitable.

The process may be better understood by a specific example, as follows:

I have operated with my process on an oil that begins to crack at about 750° F. but ordinarily producing a low yield of gasoline. By heating this oil to about 800° F. the yield of gasoline was increased, and by 75 heating the oil to 850° F. or as high as 900° F. the yield of gasoline was as high as 30% of the original stock employed. This latter temperature may be too high in practice to make the process profitable and the refiner 80 might have to be contented with a lower yield but longer running time, the decreased cost of operation of the longer running time compensating for the lower yield.

It is of paramount importance that the 85 pressure employed in this process be sufficiently high to prevent vaporization of the oil in the tubes 16, excepting, possibly, to an inconsiderable and negligible degree, since such vaporization would cause rapid deposition of carbonaceous material in the tubes 90 and consequent quick fouling thereof. In practice I have successfully employed, and prefer, a pressure of at least 60 atmospheres and as high as 1,000 to 1,200 pounds per 95 square inch and even higher for some oils. The pressure to be employed is dependent in a great measure upon the character of the oil being treated and the temperature to which it is necessary to raise the oil in the 100 cracking operation, since the higher the temperature employed the greater the pressure required to prevent any substantial vaporization of the oil.

It is to be noted that the reduction in 105 temperature of the cracked liquid hydrocarbons to or below the vaporizing temperature of the low boiling-point hydrocarbon which it is desired to recover enables me to avoid the production of a homogeneous 110 vapor such as that made by Benton in his production of illuminating oil. Benton's process enabled him to increase the production of illuminating oils and decrease the production of benzine, while by the operations performed in my apparatus the production of gasoline is increased and that of the less valuable intermediate fractions is decreased. This result is effected in the apparatus shown by employing cracking 115 temperatures of from 750° F. to 1,200° F., or even higher for some oils, and pressures in excess of 500 pounds per square inch.

A broad process that can be performed in this apparatus is not claimed herein but is 125 the subject of my co-pending application filed December 12, 1919, Serial No. 344,406 the process claims in this case being limited to a feature not disclosed in my co-pending application.

I am aware that the mere cracking of liquid hydrocarbons under pressure is not new and also that to merely cool the cracked hydrocarbons while liquid is not new. 5 Fenchelle in his British Patent No. 6547 of 1914 and Renard in his French Patent No. 462,286 of November 19, 1913, both disclose these two steps. However, Fenchelle does not cool the cracked hydrocarbons to a temperature 10 sufficiently low to prevent vaporization of the lighter hydrocarbons when the pressure is released. But my apparatus can be operated to cool the cracked hydrocarbon while in liquid form to a temperature below the vapor tension of the lighter hydrocarbons so as to obtain in liquid form the lighter as well as the heavier hydrocarbons, the hydrocarbons of different boiling points 15 forming, in this instance, a mechanical mixture which may be allowed to stand for a week or two for more complete polymerization so as to increase the yield of low boiling point hydrocarbons. This mixture or crude equivalent can subsequently be fractionated 20 in any suitable apparatus. Furthermore my apparatus can be operated to prolong the cracking operation with its resultant increased yield of low boiling hydrocarbons and also to promote polymerization of the 25 unstable hydrocarbons, such reaction being very rapid under the prolonged heating secured in the digester. In conjunction with this, the deposition of carbon will take place in a chamber that can be readily 30 cleaned of carbon and polymerization products. This is my second operation and it precedes the cooling or the fractionating operation of other patentees. The apparatus disclosed herein can be operated to immediately 35 fractionate the hydrocarbons as soon as the cracking is effected, thus conserving heat. In another instance the apparatus operates to cool the cracked liquid hydrocarbons sufficiently to prevent vaporization 40 of the heavier, but not the lighter, hydrocarbons when the pressure is subsequently released, and then the apparatus operates to step down the temperature to separate the hydrocarbons of different boiling points, 45 one at a time. This may be done at atmospheric pressures, or under pressures greater than atmospheric and less than the vapor tension of the hydrocarbons which it is the object of the refiner to obtain. It has also 50 been seen that the apparatus can operate to fractionally condense by stepping down the pressures as well as the temperatures, so that the condensing occurs under predetermined pressures as well as temperatures. In 55 still another instance the apparatus operates to cool the cracked liquid hydrocarbons sufficiently to maintain the heavier hydrocarbons in a liquid state while permitting the lighter hydrocarbons to vaporize when the 60 pressure is subsequently reduced to atmos-

pheric or to a pressure between atmospheric and the vapor tension of the hydrocarbon which is to be obtained. The apparatus then operates to step up the temperatures to vaporize the heavier hydrocarbons of different 70 boiling points, one at a time. This distilling may be effected at atmospheric pressures, or under pressures greater than atmospheric and less than the vapor tension of the hydrocarbons which are to be produced. The 75 apparatus can also operate to fractionate the hydrocarbons by stepping down the pressures without the addition of heat, the first lowering of pressure permitting the heaviest fractions to condense, the second 80 lowering of pressure permitting the intermediate fractions to condense, and so on.

I claim:

1. In an apparatus of the character described the combination of a furnace, a cracking coil in the furnace, means connected with the cracking coil to maintain the hydrocarbons at cracking temperature, said means also decreasing the rate of flow of the hydrocarbons after leaving the cracking coil, a pipe line connected therewith and having a discharge end, a valve located on the line between the cracking coil and the said discharge end and means to produce sufficient pressure on the hydrocarbons 90 to prevent vaporization thereof while at cracking temperature.

2. In an apparatus of the character described, the combination of a furnace, a cracking coil, a digestor of larger cross 100 sectional area than the cracking coil connected therewith, said digestor having a removable end for cleaning purposes, a pipe leading from the digestor and having a discharge end, a valve located on the line 105 between the digestor and its discharge end, and means for supplying hydrocarbons to the coil, digestor and pipe line to said valve and for keeping the hydrocarbons as they pass to the said valve through the coil, digestor and pipe line, under sufficient pressure to maintain them in a liquid condition.

3. In an apparatus of the character described the combination of a furnace, a cracking coil in the furnace, a digestor of 115 larger cross sectional area than the cracking coil connected therewith, a fractionating apparatus, a pressure regulating valve between the digestor and fractionating apparatus, and means for supplying hydrocarbons to the coil and digestor under pressure and maintaining a sufficient pressure in the system against the regulating valve to prevent vaporization of the hydrocarbons.

4. In an apparatus of the character described, the combination of a furnace, a cracking coil in the furnace, a vaporizing chamber, a plurality of fractionating condenser coils in series relation with each 120

125

130

other, tubing connecting the vaporizing chamber with the cracking coil, cooling means for the tubing, a pressure regulating discharge valve on the tubing between the

5 vaporizing chamber and the cracking coil, and means for supplying hydrocarbons to the cracking coil and for passing the hydrocarbons through the coil and tubing to said discharge valve under sufficient pressure to

10 maintain them in a liquid condition as described.

5. In an apparatus of the character described, the combination of a furnace, a cracking coil in the furnace, a plurality of 15 vaporizing chambers in series relation with each other, pressure regulating discharge valves for said chambers, tubing connecting the first of said chambers with the cracking coil, crossovers between adjacent chambers, 20 pressure regulating discharge valves on the crossovers, a pressure regulating discharge valve on the tubing between the cracking coil and the first vaporizing chamber, and means for supplying hydrocarbons to the 25 cracking coil and for passing the hydrocarbons through the cracking coil under sufficient pressure to maintain them in a liquid condition as described.

6. In an apparatus of the character described, the combination of a furnace, a cracking coil in the furnace, a plurality of 30 vaporizing chamber in series relation with each other, pressure regulating discharge valves for said chambers, tubing 35 connecting the first of said chambers with the cracking coil, cooling means for the tubing, crossovers between adjacent chambers, pressure regulating discharge valves on the crossovers, a pressure regulating discharge valve on the tubing between the chambers and the tube-cooling means and means for supplying hydrocarbons to the cracking coil and for passing the hydrocarbons through the cracking coil under sufficient 40 pressure to maintain them in a liquid condition as described.

7. In an apparatus of the character described, the combination of a furnace, a cracking coil in the furnace, a plurality of 45 fractionating stills in series relation with each other, pressure regulating discharge valves for said stills, tubing connecting the first of said stills with the cracking coil, cooling means for the tubing, crossovers 55 between adjacent stills, a pressure regulating discharge valve on the tubing between the cooling means and the first still, and means for supplying hydrocarbons to the cracking coil and for passing the hydrocarbons through the cracking coil under sufficient 60 pressure to maintain them in a liquid condition as described.

8. In an apparatus of the character described, the combination of a furnace, a cracking coil in the furnace, a digestor, a

plurality of connected fractionating condensers in series relation to each other, a vaporizing chamber, pressure regulating discharge valves for said condensers, pressure regulating discharge valves on the connections between adjacent condensers, tubing connecting the digestor with the vaporizing chamber a pressure regulating discharge valve on the tubing between the vaporizing chamber and the digestor, and means 75 for supplying hydrocarbons to the cracking coil and digestor and for passing the hydrocarbons through the cracking coil and digestor under sufficient pressure to maintain them in a liquid condition as described. 80

9. In an apparatus of the character described, the combination of a furnace, a cracking coil in the furnace, a digestor, a vaporizing chamber, a plurality of connected fractionating condensers in series relation 85 with each other, pressure regulating discharge valves for said condensers, pressure regulating discharge valves between adjacent condensers, tubing connecting the vaporizing chamber with the digestor, cooling means for the tubing, a pressure regulating discharge valve on the tubing between the vaporizing chamber and the tube-cooling means, and means for supplying hydrocarbons to the cracking coil and digestor and 90 for passing the hydrocarbons through the cracking coil and digestor under sufficient pressure to maintain them in a liquid condition as described.

10. In an apparatus of the character described, the combination of a furnace, a cracking coil in the furnace, a plurality of fractionating stills in series relation with each other, pressure regulating discharge valves for said stills, crossovers between adjacent stills, pressure regulating discharge valves on the crossovers, tubing connecting the first of the stills with the cracking coil, a pressure regulating discharge valve on the tubing between the first still and the cracking coil, and means for supplying hydrocarbons to the cracking coil and for passing the hydrocarbons through the cracking coil under sufficient pressure to maintain them in a liquid condition as described. 110

11. In an apparatus of the character described, the combination of a furnace, a cracking coil in the furnace, a plurality of fractionating stills in series relation with each other, pressure regulating discharge 120 valves for said stills, crossovers between adjacent stills, pressure regulating discharge valves on the crossovers, tubing connecting the first of the stills with the cracking coil, cooling means for the tubing, a pressure regulating discharge valve on the tubing between the first still and the tube-cooling means, and means for supplying hydrocarbons to the cracking coil and for passing the hydrocarbons through the cracking coil un-,

der sufficient pressure to maintain them in a liquid condition as described.

12. In an apparatus of the character described, the combination of a furnace, a cracking coil in the furnace, a digester of larger cross sectional area than the cracking coil connected therewith a vaporizing chamber, a series of connected fractionating condensers, pressure regulating discharge valves for the condensers, pressure regulating discharge valves on the connections between adjacent condensers, tubing connecting the vaporizing chamber with the digester, a pressure regulating discharge

10 valve on the tubing between the vaporizing chamber and the digester, and means to pump hydrocarbons into the cracking coil.

13. In an apparatus of the character described, the combination of a furnace, a cracking coil in the furnace, a digester of larger cross sectional area than the cracking coil connected therewith, a series of fractionating stills, pressure regulating discharge valves for the stills, crossovers between adjacent stills, pressure regulating discharge valves on the crossovers, tubing connecting the first of the stills with the digester, a pressure regulating discharge valve on the tubing between the first still

30 and the digester, and means to pump hydrocarbons into the cracking coil.

14. In an apparatus of the character described, the combination of a furnace, a cracking coil in the furnace, a digester of larger cross sectional area than the cracking coil connected therewith, a series of vaporizing chambers, pressure regulating discharge valves for said chambers, crossovers between adjacent chambers, pressure regulating discharge valves on the crossovers, tubing connecting the first of the chambers with the digester, a pressure regulating discharge

40 valve on the tubing between the first chamber and the digester, and means to pump hydrocarbons into the cracking coil.

15. In an apparatus of the character described, the combination of a furnace, a cracking coil in the furnace, a digester of larger cross sectional area than the cracking coil connected therewith, a vaporizing chamber, a plurality of connected fractionating condensers in series relation with each other, pressure regulating discharge valves for the condensers, pressure regulating discharge valves on the connections between adjacent condensers, tubing connecting the vaporizing chamber with the digester, cooling means for the tubing, a pressure regulating discharge valve on the tubing between

50 the vaporizing chamber and the tube-cooling means, and means to pump hydrocarbons into the cracking coil.

16. In an apparatus of the character described, the combination of a furnace, a cracking coil in the furnace, a digester of

larger cross sectional area than the cracking coil connected therewith, a series of fractionating stills, pressure regulating discharge valves for the stills, crossovers between adjacent stills, pressure regulating discharge valves on the crossovers, tubing connecting the first of the stills with the digester, cooling means for the tubing, a pressure regulating discharge valve on the tubing between the first still and the tube-cooling means, and means to pump hydrocarbons into the cracking coil.

17. In an apparatus of the character described, the combination of a furnace, a cracking coil in the furnace, a digester of larger cross sectional area than the cracking coil connected therewith, a series of vaporizing chambers, pressure regulating discharge valves for the chambers, crossovers between adjacent chambers, pressure regulating discharge valves on the crossovers, tubing connecting the first of the chambers with the digester, cooling means for the tubing, a pressure regulating discharge valve on the tubing between the first chamber and the tube-cooling means, and means to pump hydrocarbons into the cracking coil.

18. In an apparatus consisting of a furnace a continuous tubular heating coil, a digester of larger cross sectional area than the cross sectional area of the tubular coil, a top outlet connection for discharging the products from the digester and a bottom purging valve and connections connected to the digester, a pressure regulating and discharge valve, connections between the pressure regulating valve and the digester, and means for supplying hydrocarbons under pressure sufficient to prevent vaporization throughout the system of heating coils, digester and connections to the pressure regulating valve.

19. In an apparatus consisting of a furnace, a continuous tubular heating coil, a digester of larger cross sectional area than the cross sectional area of the tubular coil, connections between the digester and tubular coil, a top outlet connection for discharging the products from the digester and a bottom purging valve and connection connected to the digester, a pressure regulating and discharge valve; and a cooler in the connection between the digester and pressure regulating valve, and means for supplying hydrocarbons to the heating coil and digester and under sufficient pressure to maintain the hydrocarbons in a liquid condition throughout the heating coil, digester, cooler and to the point of pressure reduction through the pressure reducing valve.

20. In the process of treating hydrocarbons, the combination of steps consisting in heating hydrocarbons in a continuous tubular coil to a temperature sufficient to crack them and under sufficient pressure to sub-

stantially prevent vaporization thereof then reducing their rate of flow while maintaining their pressure, and then successively stepping down the pressure on the liquid hydrocarbons to different predetermined degrees to permit the separate vaporization of hydrocarbons of different boiling points.

21. In the process of treating hydrocarbons, the combination of steps consisting in heating hydrocarbons to a temperature sufficient to crack them, then reducing their rate of flow while maintaining them under sufficient pressure to substantially prevent vaporization thereof then allowing them to vaporize by successively stepping down the pressure on the liquid hydrocarbons to different predetermined degrees to permit the separate vaporization of hydrocarbons of different boiling points, and separately condensing the vapors of different boiling points.

22. In the process of treating hydrocarbons, the combination of steps, consisting in heating hydrocarbons in a single passage through a continuous tubular coil to a temperature sufficient to crack them, then reducing their rate of flow while maintaining

them under sufficient pressure to substantially prevent vaporization thereof then allowing them to vaporize, and then stepping down the pressure and the temperature of the vapors to different predetermined degrees to permit the separate condensation of hydrocarbons of different boiling points.

23. In the process of treating hydrocarbons, the combination of steps consisting in heating hydrocarbons to a temperature sufficient to crack them and under sufficient pressure to substantially prevent vaporization thereof, reducing the rate of flow and the temperature while under cracking pressure, and then stepping down the pressure and stepping up the temperature of the liquid hydrocarbons to different predetermined degrees to permit the separate vaporization of hydrocarbons of different boiling points.

Signed at Los Angeles, California, this 8th day of August, 1921.

DISCLAIMER.

1,431,772.—*John C. Black*, Destrehan, La. PROCESS AND APPARATUS FOR TREATING HYDROCARBONS TO PRODUCE THOSE OF LOWER BOILING POINTS. Patent dated October 10, 1922. Disclaimer filed August 9, 1928, by the assignee, *Gasoline Products Company, Inc.*

Hereby disclaims claims 1 and 3 of said patent, which read as follows:

"1. In an apparatus of the character described the combination of a furnace, a cracking coil in the furnace, means connected with the cracking coil to maintain the hydrocarbons at cracking temperature, said means also decreasing the rate of flow of the hydrocarbons after leaving the cracking coil, a pipe line connected therewith and having a discharge end, a valve located on the line between the cracking coil and the said discharge end and means to produce sufficient pressure on the hydrocarbons to prevent vaporization thereof while at cracking temperature."

"3. In an apparatus of the character described, the combination of a furnace, a cracking coil in the furnace, a digestor of larger cross sectional area than the cracking coil connected therewith, a fractionating apparatus, a pressure regulating valve between the digestor and fractionating apparatus, and means for supplying hydrocarbons to the coil and digestor under pressure and maintaining a sufficient pressure in the system against the regulating valve to prevent vaporization of the hydrocarbons."
